UNITED STATES PATENT OFFICE

120,767

DESIGN FOR A LAMP SHADE

Oliver H. Williams, Chicago, Ill., assignor to Industrial Lamp Corporation, Chicago, Ill.

Application October 25, 1939, Serial No. 87,853

Term of patent 14 years

To all whom it may concern:

Be it known that I, Oliver H. Williams, a citizen of the United States and a resident of Chicago, in the county of Cook and State of Illinois, have invented a new, original, and ornamental Design for a Lamp Shade, of which the following is a specification, reference being had to the accompanying drawing, forming part thereof.

Fig. 1 is a front elevational view of a lamp shade showing my new design.

Fig. 2 is a top plan view.

Fig. 3 is a side elevational view.

I claim:

The ornamental design for a lamp shade, as shown.

OLIVER H. WILLIAMS.
